[57] CLAIM

The ornamental design for an automobile body, as shown and described.

DESCRIPTION

FIG. 1 is a perspective view of an automobile body showing my new design;

FIG. 2 is a top plan view thereof;

FIG. 3 is a front elevational view thereof;

FIG. 4 is a rear elevational view thereof; and,

FIG. 5 is a left side elevational view, with the right side elevation being a mirror image thereof.

The bottom view is plain and unornamented. The broken line showing representing various automotive components in several of the drawing figures, form no part of the claimed design.
